UNITED STATES PATENT OFFICE.

WILLIAM MUESER, OF NEW YORK, N. Y.

TANK OR RESERVOIR OF REINFORCED CONCRETE.

1,301,155.

Specification of Letters Patent. Patented Apr. 22, 1919.

Original application filed April 2, 1915, Serial No. 18,661. Divided and this application filed October 17, 1917. Serial No. 197,135.

To all whom it may concern:

Be it known that I, WILLIAM MUESER, a citizen of the United States, residing at 1741 Clay avenue, city of New York, in the 5 county of Bronx and State of New York, have invented certain new and useful Improvements in Tanks or Reservoirs of Reinforced Concrete, of which the following is a specification.

10 This invention relates to tanks or reservoirs adapted to contain water and made of reinforced concrete and is divided out from my application, filed April 2, 1915, Serial No. 18,661.

15 In an application for Letters Patent of the United States filed by me September 14th, 1911, and recently allowed, I have described a reinforced concrete tank for this purpose comprising essentially a bottom, a 20 separate wall mounted thereon, and a joint between the wall and the bottom whereby movement between them may be facilitated, and the subject-matter of this application may be considered an improvement on the 25 invention described in that application.

Experience has developed the fact that when a reservoir of this character has to be built on sandy, gravelly or other soil of an elastic or compressible nature, or when such 30 soil lacks uniformity over its entire surface, it will happen that after filling the reservoir to its maximum the weight of the same, in addition to the weight of the fluid contents, will cause a settlement of the bottom 35 into the soil, but as soon as the reservoir is emptied only the weight of the wall will press on the outer rim of the bottom. The middle part of the bottom not being thus under downward pressure of the fluid will 40 tend to lift under the influence of the elasticity of the soil, while the weight of the wall will keep the outer edge of the bottom down. Under such circumstances certain bending stresses are developed likely to 45 crack the bottom, and one object of this present invention is to provide means for lessening this tendency or preventing it.

In addition to the means which I described for facilitating the movement of the 50 circular wall in the patent application referred to, I have found it desirable to make a construction of the wall whereby its bottom where it contacts with the upper surface of the bottom of the tank shall be slightly 55 inclined downwardly so as to more readily

overcome the frictional resistance resulting from the weight of the wall on the bottom when the tank is being filled.

I have also provided a more efficient means for reinforcing the wall, as will be herein- 60 after described in detail.

In the drawings, Figure 1 is a front elevation in miniature of a tank or reservoir embodying my invention; Fig. 2 is a vertical section through the lower portion of the 65 wall and the corresponding adjacent portions of the bottom; Fig. 3 is a top plan view of a portion of the bottom with a portion of its upper surface shown cut away to disclose the reinforcing members in two planes 70 beneath the same; Fig. 4 is a vertical section of a portion of the bottom showing the radial reinforcing members arranged in groups of three.

In the drawings, 20 designates generally 75 the bottom of the reservoir. In the form illustrated, it is shown as a comparatively flat disk having a relatively thin inner section 21 and a relatively thicker outer annular section 22 upon which the wall rests, 80 an intermediate wedge shaped section 23 joining the inner and outer sections and having a constantly increasing cross-sectional area from the inner section outwardly. The upper surface of the disk is, in the example 85 illustrated, substantially plane and at its outer edge it is provided with an annular recess 24 having a bottom 25, upon which the wall rests, slopes downwardly and outwardly to a flange 26 forming a gutter to 90 collect overflowing water which is carried to the sewer by pipes 27. A depression 28 in the upper surface of the flange serves to carry off water, filling the gutter if the pipes 27 are clogged. Water is thus kept away 95 from the foundation of the structure.

The reinforcing members of the bottom disk are arranged in two series. One comprises a series of radial bars arranged in three lengths, viz. one length 30 along the 100 upper part of the inner section 21, another length 31 along the lower part of the section 23, and another length 32 along the lower part of the section 22. Circular bars 33 are arranged at intervals transverse to the 105 lengths 32. This series of bars is adapted to take care of the bending stresses produced in the bottom and liable to crack the concrete. In Fig. 4 there is shown an arrangement in which this series of bars is ar- 110

ranged in groups of three, the middle oblique lengths 31 being arranged at varying distances from the edge of the section 23.

The second series of bars consists of a series of two sets 34 and 35 arranged at right angles to each other in the upper part of the bottom disk. These are intended to take care of local stresses and may be arranged in the upper part of the disk, as shown, or in its lower part or in any intermediate plane.

The wall 40, in the example illustrated, is cylindrical in form. It is obvious that it might be of any form of polyhedron, the cylinder being the ultimate form. It is of suitable thickness, which may vary as the exigencies of the situation demand, and it is preferably provided with a bottom surface 41 beveled to correspond to the surface 25 of the recess 24 in which it rests.

20 I claim:—

1. In a reservoir or tank, a bottom comprising an inner disk section, an annular conical section, and an outer disk section, all of concrete, and reinforcing means therefor, including a series of substantially radial bars having their inner portions embedded in the upper portion of the inner disk section, their outer portions embedded in the lower portions of the outer disk section and their intermediate portions embedded in the conical section.

2. In a reservoir or tank, a bottom comprising a relatively thin central disk section and a relatively thick outer disk section, said sections being of concrete, and radial reinforcing elements embedded in the upper portion of the inner section and extending downwardly and embedded in the lower portion of the outer section.

40 3. In a reservoir or tank, a bottom comprising a relatively thin central disk section and a relatively thick outer disk section, said sections being of concrete, reinforcing elements embedded in and extending from the lower portion of the thinner section into the upper portion of the thicker section, and reinforcing elements embedded in the upper portion of the thinner section and extending into the lower portion of the thicker section.

50 4. In a reservoir or tank, a bottom comprising an inner disk section, an annular conical section and an outer disk section, all of concrete and provided with means for reinforcing the same including a series of radial bars embedded in all three sections, all the bars being arranged in a horizontal plane in the upper part of the inner section, bent into an oblique plane in the lower part of the conical section and bent again into a horizontal plane in the lower part of the outer section.

60 5. In a reservoir or tank, a bottom comprising a relatively thin central disk section and a relatively thick outer disk section,

said sections being of concrete, reinforcing elements embedded in and extending from the lower portion of the thinner section into the upper portion of the thicker section, and substantially radial reinforcing elements 70 embedded in the upper portion of the thinner section and extending into the lower portion of the thicker section.

6. In a reservoir or tank, a bottom comprising an inner disk section, an annular conical section and an outer disk section, all of concrete and provided with means for reinforcing the same including a series of radial bars embedded in the inner section, bent to conform to the slope of the conical section and bent again and embedded in the outer section, in combination with circumferential bars arranged in the outer section.

7. In a reservoir or tank, a bottom comprising an inner disk section, an annular conical section and an outer disk section, all of concrete and provided with means for reinforcing the same including a series of radial bars embedded in all three sections, all the bars being arranged in a horizontal plane in the upper part of the inner section, bent into an oblique plane in the lower part of the conical section and bent again into a horizontal plane in the lower part of the outer section, in combination with circumferential bars arranged in the outer section.

8. In a reservoir or tank, a bottom comprising an inner disk section, an annular conical section and an outer disk section, all of concrete and provided with means for reinforcing the same including a series of radial bars embedded in all three sections, all the bars being arranged in a horizontal plane in the inner section, bent into an oblique plane in the conical section and bent again into a horizontal plane in the outer section, in combination with circumferential bars arranged in the outer section.

45 9. In a reservoir or tank, a bottom comprising an inner disk section, an annular conical section and an outer disk section, all of concrete and provided with means for reinforcing the same including a series of radial bars embedded in the inner section, bent to conform to the slope of the conical section and bent again and embedded in the outer section, in combination with a net work 110 of bars arranged in the upper part of all the sections.

10. In a reservoir or tank, a bottom comprising an inner disk section, an annular conical section and an outer disk section, all of concrete and provided with means for reinforcing the same including a series of radial bars embedded in all three sections, 125 all the bars being arranged in a horizontal plane in the upper part of the inner section, bent into an oblique plane in the lower part of the conical section and bent again into a horizontal plane in the lower part of the outer section.

outer section, in combination with a net work of bars arranged in the upper part of all the sections.

11. In a reservoir or tank, a bottom comprising an inner disk section, an annular conical section and an outer disk section, all of concrete and provided with means for reinforcing the same including a series of radial bars embedded in all three sections, all the bars being arranged in a horizontal plane in the inner section, bent into an oblique plane in the conical section and bent again into a horizontal plane in the outer section, in combination with a net work of bars arranged in all the sections.

12. In a reservoir or tank, at bottom comprising an inner disk section, an annular conical section and an outer disk section, all of concrete and provided with means for reinforcing the same including a series of radial bars embedded in the inner section, bent to conform to the slope of the conical section and bent again and embedded in the outer section, in combination with circumferential bars arranged in the outer section and a net work of bars arranged in all the sections.

13. In a reservoir or tank, a bottom comprising an inner disk section, an annular conical section and an outer disk section, all of concrete and provided with means for reinforcing the same including a series of radial bars embedded in all three sections, all the bars being arranged in a horizontal plane near the upper part of the inner section, bent into an oblique plane near the lower part of the conical section and bent again into a horizontal plane near the lower part of the outer section, in combination with circumferential bars arranged in the outer section and a net work of bars arranged in all the sections.

14. In a reservoir or tank, a bottom comprising an inner disk section, an annular

conical section and an outer disk section, all of concrete and provided with means for reinforcing the same including a series of radial bars embedded in all three sections, all the bars being arranged in a horizontal plane in the inner section, bent into an oblique plane in the conical section and bent again into a horizontal plane in the outer section, in combination with circumferential bars arranged in the outer section and a net work of bars arranged in all the sections.

15. In a reservoir or tank, a bottom comprising an inner disk section and an outer wall supporting section integral therewith and of greater thickness than the inner disk section, said bottom being formed of concrete, substantially radial reinforcing bars embedded in both the inner and outer sections, and a net-work of crossed reinforcing bars also embedded in the inner and outer sections, the radial and crossed bars being disposed in different planes.

16. In a reservoir or tank, a bottom comprising an inner disk section and an outer marginal wall supporting section of greater thickness than the inner section, and depending below the same, said bottom being formed of concrete, a series of radially disposed bars having their inner portions embedded in the upper part of the inner disk section and their outer portions embedded in the lower part of the marginal section, and a net-work of crossed bars having their inner portions embedded in the lower portion of the inner disk section and their outer portions embedded in the upper part of the outer marginal section, the sets of crossed and radial bars crossing substantially at the junction of the inner and outer sections.

In testimony whereof I affix my signature.

WILLIAM MUESER.
